UNITED STATES PATENT OFFICE.

SAMUEL E. WALES, OF ORFORD, ASSIGNOR TO HIMSELF AND JAMES H. WILLIAMS, OF WARREN, NEW HAMPSHIRE.

IMPROVEMENT IN EXTENSION TABLES.

Specification forming part of Letters Patent No. **137,516**, dated April 1, 1873; application filed March 21, 1873.

To all whom it may concern:

Be it known that I, SAMUEL EDWIN WALES, of Orford, in the county of Grafton and in the State of New Hampshire, have invented a new and useful Improvement in Extension Tables; and I do hereby declare that the following is a full, clear, and exact description thereof, reference being had to the annexed drawing making a part of this specification, in which—

Figure 1 is a bottom view of my improved table extended. Fig. 2 is a top view of the same contracted. Fig. 3 is a transverse section. Fig. 4 is a detail view of the catch.

The same letters of reference are used in all the figures in the designation of like parts.

The nature of my invention consists in constructing the major part of the top of an extension table of independent transverse rails supported upon an extensible frame-work underneath, and connected together by elastic bands to draw them closely together in the contracted state of the table and to hold them severally at equal distances apart when the table is extended.

To enable those skilled in the art to make and use my invention, I will now proceed to describe its construction and operation.

The frame-work of the table consists of two sections sliding on each other, one section being composed of a rectangular frame with broad longitudinal bars A and A¹ and supported upon four legs, the other of two narrow parallel bars, B and B¹, which are fitted to slide in dovetailed grooves in the top of the bars A and A¹, and are united together by a cross-bar at their outer ends, where they are supported by two legs. Boards A² and B², secured upon the respective sections of the supporting frame-work at their outer ends, form the fixed end parts of the top, each carrying a leaf, A³ and B³, respectively, which, when turned up, are supported by the fly-rails C. The top, between the fixed end boards, is composed of a series of transverse rails, D, enough of them being employed to completely fill the space

between the end boards when the table is in its contracted state. These rails are provided with transverse dovetailed grooves d and d' upon their under sides, hooking with one edge over the dovetailed outer edges of the bars A and A¹, and with the other edge over the dovetailed inner edges of the bars B and B¹, as clearly shown in Fig. 3, offsets being cut in the top of the bars A and A¹, so that the rails can reach full thickness to the inner edges of the bars B and B¹. The rails are connected together at opposite ends by elastic bands E and flexible but practically inelastic bands F, the latter being employed to limit the extension of the top. These bands are nailed to the several rails separately, as shown. A hook, G, may be used to lock the two sections of the frame-work of the table together when it has been contracted. Locking devices, composed of a bolt, H, inserted in an aperture in the bar A, and actuated by a spring, h', to engage with notches b, cut in the bar B, are employed to hold the table in an extended state. The head h of the bolt bears against an inclined or cam-shaped plate, I, so that by turning the head the bolt can be retracted out of engagement with the notches.

What I claim as my invention, and desire to secure by Letters Patent, is—

1. An extension table, the top of which is composed of two fixed end boards and an intermediate extensible series of flexibly-connected transverse rails, substantially as described.

2. The combination of the two-part frame-work end boards A² and B², rails D, elastic bands E, and flexible but inelastic bands F, substantially as specified.

3. The bolt H h, spring h', inclined plate I, in combination with bar A and bar B having notches b, substantially as described.

SAMUEL EDWIN WALES.
